[57] CLAIM

The ornamental design for combination stadium seat, cushion and cape carrying case, as shown and described.

DESCRIPTION

FIG. 1 is a perspective view of my combination stadium seat, cushion and cape carrying case showing my new design;

FIG. 2 is a front elevational view thereof;

FIG. 3 is a side elevational view with opposite side being a mirror image thereof;

FIG. 4 is a rear elevational view thereof;

FIG. 5 is a top plan view thereof;

FIG. 6 is a bottom plan view thereof;

FIG. 7 is a perspective view in closed position;

FIG. 8 is a top plan view thereof in closed position;

FIG. 9 is a side elevational view in closed position with the opposite side being a mirror image thereof;

FIG. 10 is a bottom plan view thereof in closed position;

FIG. 11 is a front elevational view thereof in closed position; and,

FIG. 12 is a rear elevational view thereof in closed position.
